FREQUENCY MODULATED WAVE
GENERATORJohn A. Rankin, Port Washington, N. Y., assignor
to Radio Corporation of America, a corporation
of Delaware

Application November 19, 1940, Serial No. 366,229

5 Claims. (Cl. 179—171.5)

My present invention relates to signal generators for frequency modulated waves, and more particularly to a signal generator capable of producing frequency modulated waves of substantially uniform amplitude.

Frequency modulated wave broadcasting is assigned at present to the 43 to 50 megacycle band. Frequency modulated receivers are of the super-heterodyne type, and employ an intermediate frequency channel in the 2 to 4 megacycle range. Hence, in receiver development work signal generators are utilized to cover the aforesaid signal frequency band and the intermediate frequency range. While a deviation of 100 kilocycles is considered ample for the 200 kilocycle wide channel specified for frequency modulated wave broadcasting, in investigating frequency modulated wave phenomena it is desirable to have considerably greater deviation available. For example, a maximum deviation of 500 kilocycles is desirable. By "deviation," as used in this application, is meant the frequency departure of the modulated radio frequency carrier above or below its unmodulated value.

In addition to the aforesaid wide frequency deviation it is desirable to have signal generators capable of handling modulation frequencies up to 15,000 cycle, since frequency modulation receivers are largely of higher fidelity than conventional broadcast receivers. One of the problems in signal generators has been substantially to eliminate amplitude modulation from the output of the frequency modulation signal generator. Usually in the case of frequency modulation generators the amplitude modulation introduced during the modulation process has been subsequently removed by some form of amplitude limiter. Particularly in the case of a frequency modulation system of the type wherein quadrature circuit is utilized in conjunction with the oscillator to produce frequency variation thereof, amplitude modulation effects are introduced by virtue of the reactance control tube.

It may be stated to be one of the main objects of my present invention to provide a frequency modulated wave generator with constant output voltage amplitude, and wherein the usual limiter network is dispensed with; the constant output voltage amplitude being secured by utilizing the modulating source itself substantially to eliminate any amplitude modulation introduced in the oscillator voltage during the modulation process.

Another important object of this invention is to provide, in general, a method, and means for, frequency modulating oscillations produced by

an oscillator network, and the modulated oscillations being maintained of substantial constant amplitude by utilizing the modulation source to counteract any amplitude modulation effects which may arise during the frequency modulation of the oscillator output.

Still another object of this invention may be stated to reside in the provision of an oscillator network equipped with a reactance control tube whose function it is to frequency modulate the produced oscillations in correspondence with applied modulating audio frequency voltage, and the applied modulating voltage being simultaneously employed to control an electron discharge device associated with the oscillator in a manner such as substantially to eliminate any amplitude modulation effects produced during the frequency modulation step.

Still other objects of my invention are to improve generally the efficiency and simplicity of frequency modulated wave generators, and more particularly to provide a frequency modulated signal generator with constant output voltage amplitude which is not only reliable in operation, but is economically manufactured and assembled.

The novel features which I believe to be characteristic of my invention are set forth in particularity in the appended claims; the invention itself, however, as to both its organization and method of operation will best be understood by reference to the following description taken in connection with the drawing in which I have indicated diagrammatically several circuit organizations whereby my invention may be carried into effect.

In the drawing:
Fig. 1 shows a circuit diagram of a frequency modulated signal wave generator embodying the invention,

Figs. 2 and 3 show respectively different modifications of the invention.

Referring now to Fig. 1 there is shown a tube 1 which may be of the 6J5 type which is provided with a plate 2 connected to a source of positive potential through a radio frequency choke coil 3, the plate end of the coil being by-passed to ground through a condenser 4. The grid 5 of the oscillator tube is connected to the high potential side of the oscillator tank circuit by a direct current blocking condenser 6. The grid side of the blocking condenser is connected to the cathode lead 7 by the grid leak resistor 8. The tank circuit comprises the coil 9 whose low potential end is established at ground potential.

The variable condenser 10 in shunt with coil 9 is utilized to vary the tuning of the oscillator circuit over a range of frequencies. For example, the oscillator frequency range could be 4.35 to 4.85 megacycles, and cascaded frequency multipliers could be used subsequent to the oscillator to provide such harmonics of the fundamental oscillator frequency as is desired. The cathode of tube 1 is connected through lead 7 to an intermediate point on coil 9. It will be seen that the oscillator circuit is a conventional Hartley type circuit. Oscillation voltage produced across the tank circuit 9-10 may be taken off at the high potential end of coil 9, and transmitted through coupling condenser 11 to frequency multipliers and to an output attenuator.

Frequency modulation is accomplished by the use of a quadrature circuit operating on the oscillator to produce frequency variation thereof in correspondence with applied modulating audio frequency voltage. There is connected, for this purpose, in shunt with the tank circuit a resistor 12 and condenser 13 in series. The quadrature tube itself is designated by numeral 14, and may be a tube of the 6AG7 type. This tube has its cathode at ground potential, while its plate 15 is supplied with positive potential through a radio frequency choke coil 16. The screen grid of the tube is connected to the source of positive potential through a voltage reducing resistor 17. The control grid 18 of the quadrature tube is connected through the condenser 19 to the junction of resistor 12 and condenser 13. Hence, alternating voltage developed across condenser 13 is impressed on the grid 18.

The plate 15 is connected to the high potential end of coil 9 through a direct current blocking condenser 20, and it will be noted that the plate to cathode impedance of quadrature tube 14 is connected in shunt across the tank circuit 9-10. The modulation voltage source is conventionally represented at 21, the modulation voltage, which is an audio source, being applied to grid 18 through the radio frequency choke coil 22. A direct current bias source may be arranged in series between ground and the modulation voltage source so as to apply a desired negative bias to the control grid 18, the numeral 23 designating the grid bias source.

Frequency modulation of the generated oscillations is accomplished in the following manner. If resistor 12 is large in comparison with the reactance of condenser 13 at the oscillator frequency, the current will be in phase with the tank voltage. However, the voltage across condenser 13 due to this current will lag the current by 90 degrees. The quadrature voltage is supplied to grid 18 through condenser 19, and the plate of the quadrature tube is in turn connected back to the tank circuit. The plate current of tube 14 varies at radio frequency in response to the radio frequency voltage on the grid 18. Since the radio frequency plate current is in lagging quadrature with the voltage across the tank circuit, it is equivalent to connecting a shunt inductance across coil 9 thus modifying the oscillator frequency.

The magnitude of the reflected, or simulated, shunt inductance depends on the mutual conductance of quadrature tube 14. Hence, if the mutual conductance is varied by the audio modulation voltage from source 21, the frequency of the oscillator is varied at the audio rate thereby producing frequency modulation of the generated oscillation frequency. Any variation in the

oscillator amplitude with quadrature tube mutual conductance corresponds to amplitude modulation. If the constants are adjusted to produce large frequency deviation, the oscillator amplitude will vary. Furthermore, if the amplitude of the audio voltage applied to the grid of a quadrature tube fails to produce a linear frequency deviation, amplitude distortion results. Employing an amplitude limiter subsequent to the oscillator causes the generation of harmonics of the fundamental radio frequency, and then it is necessary to utilize networks in the output circuit of the limiter to eliminate such harmonics. In accordance with my present invention a device 10 is utilized to make the oscillator input uniform 15 regardless of the amplitude of the modulating voltage applied to the grid of the quadrature tube. In other words, in accordance with the present invention the modulated oscillator voltage fed through condenser 11 has its frequency deviation proportional to the amplitude of the modulating voltage, while the frequency of the modulating voltage determines the rate of change of the predetermined tank frequency.

20 In order to accomplish this step of maintaining the modulated oscillation voltage free of amplitude variation, there is utilized a tube 24 whose cathode is established at ground potential. The plate 25 is connected to the plate 15 of quadrature tube 14. The grid 26 of tube 24 is connected by lead 27 and adjustable tap 27' to a resistor shunted across the secondary of transformer 27''. The bias source 23' biases grid 26. The primary of 27'' is across source 21. 25 It will now be seen that the plate to cathode impedance to tube 24 is connected in shunt across tank circuit 9-10. Hence, the tube 24 acts as a varying load on the oscillator tank circuit when the grid 26 is energized with audio 30 voltage from source 21 which is of the proper phase and amplitude. In other words, any amplitude modulation effects introduced by virtue of source 21 acting on tube 14 is substantially compensated for by the action of the source 40 21 on the grid of tube 24. The result of this compensation is to insure an output from the tank circuit which is substantially free from amplitude variation. It may be pointed out that for the audio modulation voltage source there 45 50 may be employed a 400 cycle audio oscillator, this source being sufficient to produce full deviation over the required bands of frequency.

The action of tube 24 of Fig. 1 in eliminating the amplitude modulation caused by the frequency modulation process of tube 14 is as follows. First it is well to explain the manner of amplitude modulation caused by the quadrature tube. As an audio modulation voltage is applied to the grid of tube 14 the G_m thereof is effectively changed. The radio frequency voltage applied to grid 18 is not exactly at 90 degrees phase to that existing across the tank circuit, but has a residual component that is in phase with the tank circuit voltage which when amplified by tube 14 appears in shunt with the tank circuit and is resistive. Hence, this causes a damping of the tank circuit. This damping, as well as the inductance that is shunted across the tank circuit, varies in amplitude as dictated by the audio modulation applied to the grid of tube 14. The inductive component results in a frequency shift of the oscillator frequency, while the resistive component results in an amplitude variation of the oscillator voltage. During the 55 60 65 70 75 positive half of the audio modulation cycle the

damping is greatest; hence the oscillation voltage is least. Conversely, during the negative half of the audio modulation cycle the damping is least, hence the oscillation voltage is greatest. Tube 24, which is termed the "Constant amplitude tube" is shunted across the oscillator tank circuit, and presents a resistance load, or damping to the tank circuit. If the damping caused by tube 24 is made equal and opposite in phase to the damping caused by the control tube 14 then the total damping over the cycle will be constant, and, hence, the oscillator voltage will be constant. This may be done by applying to the grid of tube 24 the same audio modulation voltage as that applied to the grid of tube 14. However, the phase must be reversed 180 degrees so that when maximum damping due to tube 14 occurs, minimum damping due to tube 24 will occur. The amplitude of the voltage applied to the grid of tube 14 as well as the operating bias and tube type would be chosen to provide the correct damping.

In Fig. 2 there is shown the oscillator circuit, the quadrature tube network being omitted since it can be exactly the same as that shown in Fig. 1. In this case constant oscillator amplitude is maintained by connecting tube 24 is shown. The cathode of the tube is connected to one end of choke coil 3 through a resistor 30. The plate 25 is connected to the +B terminal of the direct current source, while the control grid 26 is connected to the lower end of resistor 30 through a grid leak resistor 31. The grid 26 is connected to the modulation voltage source 21 (not shown in Fig. 2) through a direct current blocking condenser 32. Any amplitude variation introduced into the modulated oscillator voltage is corrected by virtue of the action of tube 24. The audio voltage applied to grid 26 varies the plate voltage of the oscillator tube at an audio rate. The audio voltage applied to grid 26 is chosen in phase and amplitude to compensate for the amplitude variation in the modulated oscillator voltage output.

A separate constant amplitude tube does not have to be employed since there may be utilized a common electron discharge tube to perform both the functions of generating oscillations as well as compensating for amplitude variation. Thus, in Fig. 3, where again the quadrature network has been omitted, the numeral 40 designates an electron discharge tube which has arranged between its cathode 41 and plate 42 four control grids. The grid 43 functions as the oscillator grid, while the plate 42 is connected to a source of positive potential through the radio frequency choke coil 44. The plate end of the coil is returned to ground through the capacity 45. The plate 42 then functions as the oscillator anode. The grids 46 and 47 are connected together, and are established at a positive potential by virtue of the connection through resistor 48 to the positive terminal end of coil 44. The grid 50, located between the positive screening grids 46 and 47 has applied to it the audio voltage from the modulation voltage source 21. The voltage is applied through coupling condenser 60, the grid side of condenser 60 being connected to ground through the leak resistor 70. Here, again, by applying audio voltage of correct phase and amplitude to grid 50 amplitude variation in the frequency modulated oscillation voltage developed across tank circuit 9-10 is substantially eliminated.

The constant amplitude tube 24 of Fig. 2 oper-

ates to eliminate the amplitude modulation by changing the plate voltage of the oscillator. It is well known that as the plate voltage of an oscillator tube is varied the oscillation strength, or voltage, will also be varied in a similar manner. So, if the audio modulation voltage is applied to the grid of tube 24 in the same phase as that applied to the grid of the quadrature tube, then as the quadrature tube increases the damping across the tank circuit, which will lower the tank voltage, the plate supply voltage is increased. This will increase the tank voltage; hence, over the operating cycle of modulation voltage the oscillation voltage will be constant.

In Fig. 3 the modulation voltage is applied to grid 50 of the oscillator tube 40. This in effect changes the G_m of the oscillator to hold the oscillator strength constant. If the G_m of an oscillator tube is increased the oscillation strength will be likewise increased. Conversely, if the G_m is decreased the oscillation strength will be decreased. If the modulation voltage that is applied to the quadrature tube grid is applied to a grid of the oscillator in the same phase, then as the damping due to the quadrature tube is increased, which lessens the oscillation strength, the G_m of the oscillator will be increased. This increases the oscillation strength; hence, the two act in opposition which results in a constant oscillator voltage.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In an oscillation generator of the type comprising a tube having electrodes including a plate coupled to a source of supply voltage and to a network for producing oscillations of a predetermined frequency, an electron discharge device operatively associated with said network to provide a simulated reactive effect therefor, an audio modulation voltage source connected with said device for varying the magnitude of said reactive effect thereby to frequency modulate said oscillations, and a second device operatively associated with said network to provide compensation for amplitude modulation effects introduced during frequency modulation of the oscillations, and said second device being connected to said modulation source whereby amplitude modulation effects produced by said modulation source are substantially eliminated, said network including an oscillation tank circuit, said electron discharge device having input and output electrodes, a reactive path connected in shunt with said tank circuit and providing an alternating voltage which is in quadrature with tank circuit voltage, means for impressing the quadrature voltage on said input electrodes, said output electrodes having their impedance existing therebetween connected across said tank circuit to provide said reactive effect, and said second device being an additional electron discharge device with input and output electrodes, said output electrodes of said last device being connected in series between said oscillator supply voltage source and oscillator tube plate, said modulating voltage being coupled to said input electrodes of said additional device.
2. In an oscillation generator of the type com-

prising an electron discharge device having a plurality of electrodes coupled in a reactive network for producing oscillations of a predetermined frequency, said tube having an additional electrode, an additional electron discharge device operatively associated with said network to provide a simulated reactive effect therefor, an audio modulation voltage source connected with said additional device for varying the magnitude of said reactive effect thereby to frequency modulate said generated oscillations, and a second means operatively associated with said network to provide compensation for amplitude modulation effects introduced during the frequency modulation of the oscillations, said second means being connected to said modulation source whereby amplitude modulation effects produced by said modulation source are substantially eliminated, said network including an oscillation tank circuit, said additional electron discharge device having input and output electrodes, a reactive path connected in shunt with said tank circuit and providing an alternating voltage which is in quadrature with the tank circuit voltage, means for impressing the quadrature voltage on said input electrodes, said output electrodes having their impedance existing therebetween connected across said tank circuit to provide said reactive effect, and said modulating voltage source being connected to said additional electrode of said first electron discharge device to control its electron discharge thereby eliminating amplitude changes across said tank circuit.

3. In a wave length modulation system, an oscillation generator including a tube generator having a cathode, a grid and a plate coupled by a tuned tank circuit which determines in part at least the frequency of the oscillations generated, a reactance tube having an anode, a cathode, and a control grid, means for impressing oscillating voltages from said tank circuit on the anode of said reactance tube, means for impressing voltages from said tank circuit on the control grid of said reactance tube, said impressed voltages being displaced substantially 90 degrees, whereby a reactive effect is produced in said reactance tube, means coupling the impedance between the anode and cathode of said reactance tube in shunt to said tank circuit to supplement the reactance of the tank circuit by the reactance of said reactance tube, a source of modulating potentials coupled with an electrode of said reactance tube to modulate the potential thereon in accordance with modulating potentials to thereby modulate the gain of the reactance tube and modulate the supplemental reactance supplied to said tank circuit to wave length modulate the generated oscillations, and means for compensating for undesired amplitude modulation produced by modulating the wave length of said oscillations comprising an electron discharge device having an anode and cathode and having an input electrode variably coupled to said source of modulating potentials, connections connecting the anode-to-cathode impedance of said device in series with the plate-to-cathode impedance of the first tube, the impedance of said electron discharge device being modulated by said modulating potentials to thereby vary the amplitude of the oscillations generated in a sense to compensate for said undesired amplitude modulations.

4. In a wave length modulation system, an oscillation generator including a tube having input and output electrodes, a source of direct current in a circuit including the output electrodes of said tube, a tuned tank circuit which determines in part at least the frequency of the oscillations generated connected with electrodes of said tube, a reactance tube having an anode, a cathode, and a control grid electrode, means for impressing oscillating voltages from said tank circuit on the anode of said reactance tube, means for impressing voltages from said tank circuit on the control grid electrode of said reactance tube, said impressed voltages being displaced substantially 90 degrees, whereby a reactive effect is produced in said reactance tube, means coupling the anode and cathode of said reactance tube to said tank circuit to supplement the reactance thereof by the reactance of said reactance tube, a source of modulating potentials, connections thereto for modulating the potential on said control grid electrode of said reactance tube to thereby modulate its gain and modulate the supplemental reactance supplied to said tank circuit to wave length modulate the generated oscillations, and means for compensating for amplitude modulation produced during said wave length modulation including an electron discharge path in said first named circuit including the output electrodes of said generator tube, a control electrode in said path, and connections between said last named electrode and said source of modulating potentials for modulating the potential on said electrode substantially in phase with modulation of the potential on the control grid of said reactance tube.
5. In a wave length modulation system, an oscillation generator including a tube having a discharge path and electrodes associated with a tuned tank circuit which determines in part at least the frequency of the oscillations generated, a reactance tube having an anode, a cathode and a control grid electrode, means for impressing oscillating voltages from said tank circuit on the anode of said reactance tube, means for impressing voltages from said tank circuit on said control electrode of said reactance tube, said impressed voltages being displaced substantially 90 degrees, whereby a reactive effect is produced in said reactance tube, means coupling the anode and cathode of said reactance tube in shunt to said tank circuit to supplement the reactance thereof by the reactance of said reactance tube, a source of modulating potentials coupled to said control grid for modulating the potential on said control grid electrode of said reactance tube to thereby modulate its gain and modulate the supplemental reactance supplied to said tank circuit to wave length modulate the generated oscillations, and means for compensating for amplitude modulation produced during said wave length modulation including a discharge path, in series with said first discharge path, a control electrode in said second path, and connections from said source of modulating potentials to said last control electrode for applying thereto modulating potentials of a phase substantially the same as the phase of the modulating potentials applied to the control electrode of said reactance tube.
